J. A. LE CAIN

FEED WATER HEATING APPARATUS

Filed Feb. 13, 1922

16 19 Inventor 22
John A. DeCain
By his Attorney
Philip (Enclosed) DeCain

UNITED STATES PATENT OFFICE.

JOHN A. LE CAIN, OF MALDEN, MASSACHUSETTS, ASSIGNOR TO WORTHINGTON PUMP AND MACHINERY CORPORATION, OF NEW YORK, N. Y., A CORPORATION OF VIRGINIA.

FEED-WATER-HEATING APPARATUS.

Application filed February 13, 1922. Serial No. 536,001.

To all whom it may concern:

Be it known that I, JOHN A. LE CAIN, a citizen of the United States, residing at Malden, county of Middlesex, and State of Massachusetts, have invented certain new and useful Improvements in Feed-Water-Heating Apparatus, fully described and represented in the following specification and the accompanying drawings, forming a part 10 of the same

This invention relates to feed water heaters for locomotive use and especially to such a system as is described and claimed in United States Letters Patent 1,350,322, patented 15 August 24, 1920 by T. C. McBride.

The especial object of the invention is to provide a simple, rigid and compact unit for attachment to the locomotive boiler so constructed and divided that the interior 20 thereof is readily accessible for cleaning and repairs by the removal of a comparatively small and light weight casting.

For a full understanding of the invention a detailed description of a locomotive feed 25 water heating apparatus embodying all the features of the invention in their preferred form will now be given in connection with the accompanying drawing, and the features forming the invention then specifically 30 pointed out in the claims.

In the drawing—

Fig. 1 is a sectional elevation of the complete apparatus;

Fig. 2 is a side elevation showing attachment to the locomotive boiler; and

Figs. 3, 4, 5, 6 are sections respectively on lines 3—3, 4—4, 5—5 and 6—6 of Fig. 1.

Referring to the drawing, A is the heat exchange chamber or heater proper to which steam passes through steam connection 11 and to which cold water is delivered through passage 12 by the cold water supply pump B, the heater chamber inlet of the passage 12 being controlled by a suitable spring-pressed spray valve 13. The heat exchange chamber is provided with a baffle 14 which aids in distributing the steam and procures a better mingling of the steam and cold water. The condensed steam and heated 50 water pass through the baffle 14 to a hot water tank C, C' in which the bucket tank D is mounted, to which the heated water

passes by over-flow. Within the bucket tank D is fixed a vertical rod or stem 15, which is hollow throughout its lower portion, upon which slides a bucket type float d, the lower end of which controls a plurality of ports 1 connecting the interior of the bucket d with the hollow portion 2 of the stem 15 upon lowering of the bucket d. The stem 15 is also provided near its lower end with a plurality of ports 3 connecting with a chamber 16, through which the excess return flow passes to cold water supply pump B under the control of one or more suction 65 valve 4.

The lower part C' of the hot water tank is connected by passage 19 to the suction chamber 20 of the hot feed water pump G. Suitable suction valves 21 and 22 are seated 70 in the upper end of the suction chamber 20 and are separated by a partition 23 arranged to provide two pulsation passages 24 and 25 connecting respectively the suction valves 21 and 22, one with the lower end and the other with the upper end of the pump G. Above the suction valves 21 and 22 are mounted suitable discharge valves 26 through which the heated water passes 75 through chamber 27 and passage 28 to a suitable delivery chamber, preferably formed as shown, comprising two chambers E and J connected by passage 18 and located upon opposite sides of the tank C'. The chamber E is separated from the tank C' 80 by inclined partition 17. The discharge connection 29 is provided with an interior extension 30 extended downward within the water in chamber J and air sealed thereby. The two chambers E and J thus form a combined air and delivery chamber, a large capacity being thus secured with a heater construction of small dimensions.

The passage 28 preferably connects with the chamber J on the same side at which 95 extension 30 is located and in line with the passage 18 connecting chambers E and J, so that any sediment carried by the water will be forced away from the extension 30 and collect within the chamber E and along 100 the side of the chamber J opposite to the extension 30, the water delivered to the boiler through 29 thus being freed from sediment and chamber E thus forming a

sediment chamber. The pumps B and G are direct connected and driven by a suitable steam cylinder K mounted thereabove.

I preferably form my feed water heater unit in two castings divided horizontally into an upper section which comprises the heater A and the cold water supply pump B, this section having integral therewith a suitable shelf or support 31 to which the 10 steam engine cylinder K is secured and a lower section comprising the lower portion of the hot water chamber C, C', the combined chambers E and J, and the hot water feed pump G, all of which, together with 15 their connecting passages, are formed in a single casting, as shown. The feed water heater apparatus is supported as a unit from the locomotive boiler L by suitable brackets 32 provided with feet 33 engaging with suitable feet 34 formed in the upper heater section 20 for securing thereto by bolts, as shown.

I also provide suitable blow out openings 5 closed by closures 6, whereby the various 25 chambers may readily be blown out and cleaned without dismantling the heater. In order to provide means for cleaning out the bucket tank D and the chamber 16, I provide these with laterally extending passages 7 and 8 provided with suitably closed blow 30 out openings.

The operation of the construction will be understood from the drawing and above description in connection with Patent No. 1,350,322 above referred to.

What is claimed is:—

1. A feed water heater unit having an upper section comprising a heater, a lower section suspended from the upper section and comprising a hot water chamber, a float tank, and a passage for delivery of excess water from the float tank, and means for attachment of the upper section to a locomotive boiler for support of the unit by the upper section.

2. A feed water heater unit having an upper section comprising a heater and a cold water supply pump cast integrally, a lower section suspended from the upper section and comprising a hot water chamber and a 40 hot water feed pump cast integrally, a float tank carried by the lower section, and means for attachment of the upper section to a locomotive boiler for support of the unit by the upper section.

3. A feed water heater unit having an upper section comprising a heater and a cold water supply pump, a lower section suspended from the upper section and comprising a hot water chamber, a float tank, an excess

water passage connecting the float tank and 60 cold water supply, and means for attachment of the upper section to a locomotive boiler for support of the unit by the upper section.

4. A feed water heater unit having an 65 upper section comprising a heater and a cold water supply pump, a lower section suspended from the upper section and comprising a hot water chamber, a sediment chamber and a hot water feed pump, and 70 means for attachment of the upper section to a locomotive boiler for supporting the unit by the upper section.

5. A feed water heater unit having an 75 upper section comprising a heater and a cold water supply pump cast integrally, a lower section comprising a hot water chamber, a sediment chamber and a hot water feed pump cast integrally, and means for attachment of the upper section to a locomotive 80 boiler for support of the unit by the upper section.

6. A feed water heater unit having an upper section comprising a heater and a hot water chamber cast integrally, and a 85 lower section comprising a hot water chamber, suction and delivery passages, and a sediment and air chamber cast integrally.

7. A feed water heater unit having an upper section comprising a heater, a hot 90 water chamber and a cold water supply pump cast integrally, and a lower section comprising a hot water chamber, suction 95 and delivery passages, a sediment and air chamber, and a hot water feed pump cast integrally.

8. A feed water heater having chamber C' receiving the heater water, pump cylinder G, suction chamber 20, delivery chamber 21, and air chamber J, all arranged substantially in line, and passages 19 and 28 around the opposite sides of the pump cylinder and connecting respectively chambers C' and 20, and chambers 27 and J.

9. A feed water heater having chamber C' receiving the heater water, pump cylinder G, suction chamber 20, delivery chamber 27 and sediment and air chambers E and J, all arranged substantially in line, passages 19 and 28 around the opposite sides of the pump 110 cylinder and connecting respectively chambers C' and 20 and chambers 27 and J, and passage 18 around chamber C' connecting chambers E and J.

In testimony whereof, I have hereunto set my hand.

JOHN A. LE CAIN.
